(57) **CLAIM**

The ornamental design for a bag for packaging, as shown and described.

DESCRIPTION

The patent or application file contains at least one drawing executed in color. Copies of this patent or patent application publication with color drawing(s) will be provided by the Office upon request and payment of the necessary fee.

1. Bag for packaging

1.1 : Perspective

1.2 : Front

1.3 : Back

1.4 : Left

1.5 : Right

1.6 : Top

1.7 : Bottom

This is a design for a bag for packaging for disposable diapers; the broken lines appearing in the front view, the rear view, the top view, and the perspective view are perforations for opening.

1 Claim, 7 Drawing Sheets
